CLAIM

The ornamental design for the aircraft passenger control console, as shown and described.

DESCRIPTION

FIG. 1 is a top perspective view of an aircraft passenger control console, showing my new design;
 FIG. 2 is a top perspective view thereof taken from an opposite end thereof;

FIG. 3 is a first end view thereof;

FIG. 4 is an opposite end view thereof;

FIG. 5 is a first side view thereof;

FIG. 6 is a second side view thereof;

FIG. 7 is a top view thereof; and,

FIG. 8 is a bottom view thereof.

In the drawings, the broken lines depict environmental subject matter only and form no part of the claimed design.
